(57) **CLAIM**

The ornamental design for a cleaning robot, as shown and described.

DESCRIPTION

Fig. 1.1 is a front view of a first embodiment of a cleaning robot showing the new design;

Fig. 1.2 is a rear view thereof;

Fig. 1.3 is a left side view thereof;

Fig. 1.4 is a right side view thereof;

FIG. 1.5 is a top view thereof;

Fig. 1.6 is a bottom view thereof;

Fig. 1.7 is a perspective view thereof;

Fig. 1.8 is a perspective view thereof featuring callout region 1.10;

Fig. 1.9 is a perspective view thereof;

Fig. 1.10 is an enlarged view of callout region 1.10 of Fig. 1.8;

Fig. 2.1 is a front view of a second embodiment of a cleaning robot showing the new design;

Fig. 2.2 is a rear view thereof;

Fig. 2.3 is a left side view thereof;

Fig. 2.4 is a right side view thereof;

Fig. 2.5 is a top view thereof;

Fig. 2.6 is a bottom view thereof;

Fig. 2.7 is a perspective view thereof;

(Continued)

Fig. 2.8 is a perspective view thereof featuring callout region 2.10;
 Fig. 2.9 is a perspective view thereof;
 Fig. 2.10 is an enlarged view of callout region 2.10 of Fig. 2.8;
 Fig. 7.1 is a front view of a third embodiment of a cleaning robot showing the new design;
 Fig. 7.2 is a rear view thereof;
 Fig. 7.3 is a left side view thereof;
 Fig. 7.4 is a right side view thereof;
 Fig. 7.5 is a top view thereof;
 Fig. 7.6 is a bottom view thereof;
 Fig. 7.7 is a perspective view thereof;
 Fig. 7.8 is a perspective view thereof;
 Fig. 7.9 is a perspective view thereof;
 Fig. 8.1 is a front view of a fourth embodiment of a cleaning robot showing the new design;
 Fig. 8.2 is a rear view thereof;
 Fig. 8.3 is a left side view thereof;
 Fig. 8.4 is a right side view thereof;
 Fig. 8.5 is a top view thereof;
 Fig. 8.6 is a bottom view thereof;
 Fig. 8.7 is a perspective view thereof;
 Fig. 8.8 is a perspective view thereof; and
 Fig. 8.9 is a perspective view thereof.
 The broken lines in Figs. 1.8, 1.10, 2.8, and 2.10 show outer boundaries of the callout regions, and form no part of the claimed design.
